ELECTRODE HOLDER

Charles E. Benner, Grosse Pointe Woods, Mich.,
assignor to Mott Steel Products Company, De-
troit, Mich., a corporation of Michigan

Application April 28, 1945, Serial No. 590,879

7 Claims. (Cl. 219—8)

1.

This invention relates to electrode holders, and particularly to an electrode holder having a handle portion screwed within the head portion for clamping the welding rod securely thereto.

While various types of electrode holders have been manufactured heretofore, it is believed that the present holder contains unique and patentable features. The holder embodies a handle portion of insulating tubular construction having a cable terminal supported therein by screws which project through the wall of the handle. The terminal has a forwardly extended tubular portion containing an internal and external thread, in the former of which a rod is threaded which projects beyond the tubular extension. The exterior threads on the tubular extension engage threads in a conducting head having a hollow interior into which the stem extends and moves longitudinally relative thereto when the head is screwed upon the terminal extension. An angularly disposed aperture extends through the head for the reception of the welding rod which is clamped against one side of the aperture by the projecting rod in the handle when the handle is turned to have the cap and terminal extension screwed into each other. A pair of insulating plates is attached to opposite sides of the head parallel to the rod to prevent the head from contacting any metal when handled by the operator or when resting on a conducting plate.

Accordingly, the main objects of the invention are: to provide an electrode holder having a truncated, pyramidal conducting head on two opposite sides of which insulating plates are secured to project therebeyond; to provide a terminal for a hollow insulating handle of an electrode holder with a tubular projection having interior and exterior threads for supporting a clamping rod on the internal threads and for producing the advancement of the rod by the movement of the thread on the exterior surface of the extension in a thread within the conducting head of the holder; to support a terminal within a hollow insulating handle of an electrode by screws which extend through the wall thereof and which are insulated by a flexible band which is snipped within a groove in which the heads of the screws are nested; to provide an electrode holder with an insulating handle for supporting a conducting head in which the welding rod is clamped and which is protected by oppositely disposed insulating plates which project beyond the edges of the head; and, in general, to provide an electrode holder which is simple in construction, positive in operation, and economical of manufacture.

Other objects and features of novelty of the

2.

invention will be specifically pointed out or will become apparent when referring, for a better understanding of the invention, to the following description taken in conjunction with the accompanying drawing, wherein:

Figure 1 is a view in elevation of an electrode holder embodying features of this invention;

Fig. 2 is a sectional view of the structure illustrated in Fig. 1, taken on the line 2—2 thereof;

Fig. 3 is a sectional view of the structure illustrated in Fig. 2, taken on the line 3—3 thereof, and

Fig. 4 is a sectional view of the structure illustrated in Fig. 2, taken on the line 4—4 thereof.

The electrode holder comprises a tubular handle 10 made of insulating material having circumferential notches 11 therein to provide a secure grip for the operator grasping the handle. A pair of oppositely disposed notches 12 is provided near the front edge of the handle for the purpose of receiving a pair of insulating plates which, when secured together, are locked on the handle to form a shield.

A cable terminal 13 is provided with a hollow interior 14 in which the end 15 of a cable 16 projects and is secured in position by a pair of set screws 17. A screw 18, which secures the terminal in position in the handle 10, has its head covered by a resilient band 19 which projects within a circumferential groove 21 in which the head is nested.

The terminal 13 has a tubular extension 22 at its forward end containing a thread 23 on its inner surface and a thread 24 on its outer surface. A clamping rod 25 has a threaded end 26 which is screwed into the interior of the extension 22 of the terminal to be disposed in fixed relation therewith.

A conducting head 27 contains a central aperture 28 in which the rod 25 projects and an enlarged aperture 29 containing a thread 31 which registers with the thread 24 on the exterior surface of the extension 22 of the terminal 13. An aperture 32 extends laterally through the end 40 of the head 27 and communicates with the aperture 28 from which a conical end 33 of the rod 25 is advanced to engage a welding electrode 34 and clamp it against the sides of the aperture 32. It will be noted from Fig. 1 that the aperture 32 is provided with flat sides 35 in angular relation to each other opposite to the conical end 33 so as to produce line contact between the welding rod 34 and each of the flat sides 35 to provide good conducting contact therebetween. This

50 maintains the resistance to the flow of current

40 45 50 55 60 65 70 75 80 85 90 95

40 45 50 55 60 65 70 75 80 85 90 95

therebetween to a minimum to prevent the undue heating of the head and rod.

The end of the head adjacent to the handle 10 is cylindrical in shape and provided with an outwardly directed flange 36 which extends substantially to the inner surface of the handle 10 as it moves in a cylindrical slot 37 formed between the terminal extension 22 and the inner surface of the handle. The sides 38 of the head 27 converge toward the forward end the same as the sides therebetween containing the aperture 32. The sides 38 of the head are covered by a pair of insulating plates 39 being secured in position by screws 41. The plates 39 are made from a material which resists burning and project a substantial amount from the side edges to protect the uninsulated faces and end from contact with a metal plate or other object while in use or when placed thereon after use. When the electrode holder is to be initially employed, the resilient band 19, the screw 18 and the cap 27 are removed to permit the removal of the terminal 13 from the handle 10. The end 15 of the cable 16 is then inserted within the aperture 14 and is retained in fixed relation thereby by tightening the set screws 17. Thereafter the terminal 13 and cable are inserted into the handle 10 from the right-hand end thereof, as viewed in the figure. The screw 18 is inserted in the position as illustrated in Fig. 2 and the band 19 is applied thereover within the slot 21 in the outer surface of the handle. The cap 27 is screwed upon the threads 24 of the terminal extension 22 and a welding rod 34 is inserted in the aperture 32 of the head. The relative rotation of the head 27 and handle 10 advances the conical end 33 of the rod 25 within the aperture 28 until it engages the rod 34 and forces it into good conducting contact with the flat faces 35 of the aperture 32 which completes an electric circuit from the cable 15 to the end of the welding electrode.

When the welding electrode has been consumed, it is only necessary to rotate the head and handle 10 relative to each other a slight amount to release the rod 34 and, after another rod has been inserted in the aperture 32, the relative rotation of the head and handle in the opposite direction clamps the rod in position within the aperture 32. It will be noted that the sides 38 of the head 27 of the holder, as well as the sides 42 disposed therebetween, taper from the rear or threaded end to the opposite or front end containing the aperture 32. This provides sufficient material to properly conduct the current to the welding electrode and produces a trim appearance to the head when insulated by the plates 39. The body of the cable terminal 13 is provided with a circumferential groove 43 and the bearing rings 44 are slotted at spaced points so as to permit air to pass from one to the other end of the handle which aids in cooling the terminal and other metal parts contained therein.

What is claimed is:

1. An electrode holder embodying a tubular handle, a cable terminal within the handle to which a cable is secured, a screw extending through the wall of the handle into the terminal for retaining it in fixed relation within the handle, a resilient band supported by said handle over the screw for insulating the screw head, a tubular extension projecting forwardly from the cable terminal having a thread on its interior and exterior surface, a rod threaded within the tubular extension, and a cap threaded onto the threads of the outer surface of the extension con-

taining a hollow interior into which the rod extends, said cap having sides which converge from the threaded to the opposite ends.

2. An electrode holder embodying a tubular handle, a cable terminal within the handle to which a cable is secured, a screw extending through the wall of the handle into the terminal for retaining it in fixed relation within the handle, a resilient band supported by said handle over the screw for insulating the screw head, a tubular extension projecting forwardly from the cable terminal having a thread on its interior and exterior surface, a rod threaded within the tubular extension, a cap threaded onto the threads of the outer surface of the extension containing a hollow interior into which the rod extends, said cap having sides which converge from the threaded to the opposite ends, and a pair of insulating plates secured to opposite sides of the head which project beyond the sides and ends, said head containing an aperture through the uninsulated sides communicating with the central aperture in which the rod threaded in the cable terminal extends.

3. In a welding electrode holder, a cable terminal having a hollow threaded extension, an insulating handle for encompassing said terminal, a screw extending through the handle for securing the terminal thereto, said handle containing a slot through which the screw extends, a resilient band of insulating material secured to said slot for insulating the head of the screw, a cap threaded on the terminal extension, a rod threaded in the aperture in the terminal extension to extend therefrom in fixed relation thereto, said cap having a hollow interior for receiving said rod, a laterally disposed aperture communicating with said first aperture into which said rod is projectable for clamping the electrode in position in said last aperture, and a pair of insulating plates secured to the sides of said cap to extend beyond the sides through which said last aperture extends.

4. In a welding electrode holder, a cable terminal having a hollow threaded extension, an insulating handle for encompassing said terminal, a screw extending through the handle for securing the terminal thereto, a rod threaded in the aperture in the terminal extension to extend therefrom in fixed relation thereto, a cap threaded on said terminal extension having a hollow interior for receiving said rod, a laterally disposed aperture communicating with said first aperture into which said rod is projectable for clamping the electrode in position in said last aperture, and a pair of insulating plates secured to the sides of said cap to extend beyond the sides through which said last aperture extends.

5. In a welding electrode holder, an insulating handle, a cable terminal in said handle having a thread, a conducting cap threaded on said handle having means for supporting an electrode, and a pair of insulating elements secured to opposite sides of said cap leaving the portion therebetween uninsulated but protected by said elements which extend beyond the exposed surfaces thereof.

6. A conducting cap having four converging sides, and a pair of insulating plates of an area greater than said sides secured to opposite sides of said cap to extend therebeyond to protect the uninsulated sides disposed therebetween.

7. A cap for an electrode holder made of conductive material and being of truncated pyramidal section having four sides sloping toward

one end, the opposite end being cylindrical in section, a pair of insulating plates secured to opposite sides of said cap and having an area greater than said sides to extend therebeyond and protect the exposed sides of said cap disposed between the plates, and a handle having a threaded end for engaging and supporting the cylindrical end of said cap, said cylindrical end containing a thread engageable with the thread on said handle.
